UNITED STATES PATENT OFFICE.

WILLIAM D. MOUNT, OF LYNCHBURG, VIRGINIA.

STORAGE DEVICE.

Application filed September 15, 1922. Serial No. 588,419.

To all whom it may concern:

Be it known that I, WILLIAM D. MOUNT, a citizen of the United States, residing at Lynchburg, in the county of Campbell and State of Virginia, have invented certain new and useful Improvements in Storage Devices, of which the following is a full, clear, and exact description.

This invention relates to the storage of fragile or lump material, to avoid breakage thereof and has particular value in the sorting and storage of lime. Lime coming from the kilns comprises a mixture of fine and coarse particles or lumps, and the latter brings a higher market price than the fine lime. It is very desirable that in storing the lime from the kilns, preparatory to packing and shipping, that breakage of the lumps or coarse particles be prevented as far as possible if a maximum market price is to be realized. An object of the invention is to provide improved means for the sorting and storage of lime, with which the breakage of the coarse lumps or particles is reduced to a minimum; with which the sorting and storage is accomplished in a simple, convenient, efficient and expeditious manner, and which is simple, and inexpensive in construction and operation. Other objects and advantages will be apparent from the following description of an embodiment of the invention and the novel features will be particularly pointed out in claims.

In the accompanying drawings:

Fig. 1 is a sectional elevation through a sorting and storage device constructed in accordance with this invention and taken substantially along the line *a*—*b* of Figure 2,

Fig. 2 is a transverse sectional elevation of the same;

Fig. 3 is a transverse sectional elevation of a portion of the same; and

Fig. 4 is a sectional elevation of a portion of the same, taken substantially along the line *4*—*4* of Figure 3.

In the illustrated embodiment of the invention, a plurality of columns 1 are tied together by cross columns 2 and tie rods 3 to form a suitable supporting frame or structure for the storage bin proper. The bin proper is formed of suitable sheet metal 4 which is dependably supported from the upper ends of the columns, and of sheet metal 5 which extends above the upper ends

of the intermediate columns, forming an air and water tight roof or cover. The walls of the lower part of the bin which are formed by the sheet metal 4, are reinforced at the ends by suitable channels or I-beams 6 which extend cross wise of the bin and horizontally, and which may, if desired, be attached to the end I-beams of the frame. The side walls of the lower part have in transverse cross section the shape of a catenary and do not need longitudinal stiffening, but if desired, suitable beams 6 may also be used, as illustrated. A partition or wall 7 is disposed across the interior of the bin in an inclined position so as to divide the interior of the bin into two storage compartments A and B. A wall or platform 8 extends from the upper end of the inclined partition 7 substantially horizontally across the upper end of the compartment A which extends beneath the inclined wall or partition. The compartment B which is formed above the inclined partition is open at the top for its entire length and for a width at least equal to that of the platform 8.

Pairs of sprocket wheels 9 and 10 are carried by shafts 9^a and 10^a that are rotatably mounted in bearings 11 and 12 which are arranged adjacent the ends of the bin, and the wheels support and drive a pair of spaced endless belts 13 that extend lengthwise of the bin over the open face of the compartment B and over and in close proximity to the substantially horizontal wall or platform 8. A motor 14 or other suitable power device is geared to one pair of the sprocket wheels, at one end of the bin, such as 10, for driving the same and causing a continuous movement of the belts. The belts are connected upon their outer faces with transversely extending scrapers 15 which are adapted to scrape any material which is deposited upon the wall or platform 8 along the same and over and upon the upper face of the inclined wall or partition 7. The endless belts, scrapers, and sprocket wheels thus form an endless carrier device.

A screening device 16 is mounted upon guide devices 17 for reciprocating movement in a direction either crosswise or lengthwise of the bin and has an inclination towards the platform 8. The screening device is provided with a suitable reticulated plate or screen 18 which is spaced above the imperforate bottom wall 19 and which is adapted

to permit of the passage therethrough of the finer particles of the lime, and to shift the coarser particles along the same and deposit them upon the platform 8 between 5 the upper and lower stretches of the endless carrier device. The lower wall 19 of the screening device terminates before reaching the platform 8 and discharges the finer particles of lime carried thereon through a 10 chute 20 into the storage compartment A of the bin. The coarser particles which are deposited upon the platform 8 by the screen 18 are carried by the scrapers 15 along the platform and over and upon the upper face 15 of the inclined wall or partition 7, and the coarser particles so deposited will slide or roll down the inclined partition at a comparatively slow speed so that when they come to rest, it will not be with sufficient 20 force to cause a breakage thereof into fine particles.

In order to reinforce the inclined partition and also to provide additional resistance to the rolling or sliding of the lumps or 25 particles down the inclined partition, I may provide upon the upper face of the partition cross strips 21 which may be in the nature of channel or I-beams which extend horizontally across the partition at different 30 levels thereon, so as to stiffen the inclined wall and also catch the lumps or coarse particles and retard their movement down the partition. As soon as a layer of the coarse particles or lumps has been formed upon 35 the inclined partition, the carrier device will continue to scrape the particles from the platform 8 over and upon the surface of the layer, and the surface of the layer will offer resistance to the rolling or sliding 40 movement of the newly deposited lumps or particles sufficient to prevent rapid movement down the same and upon the bottom wall. The carrier device will continue to deposit the material upon the upper end 45 of the layer surface and as the layer surface progresses lengthwise of the bin the carrier device will continue to deposit the coarser particles progressively thereon until the bin is entirely filled.

50 The screening device 16 may be operated in any suitable manner, but as illustrated is connected by a suitable link 22 to a crank 23 that is continuously rotated by means of a pulley 24 and a belt 25 or by any other 55 suitable source of power. The screening device will, therefore, be reciprocated back and forth continuously and when the lime is deposited upon the screen 18, the fine particles will pass through the same and fall 60 upon the plate 19 and the coarser particles will be shifted along the screen by the reciprocating movement and deposited upon the platform 8.

65 A suitable elevating device 26 may be provided adjacent the bin for carrying the lime

to a point above the screening device 16 and depositing the same through a chute 27 upon the screen 18. The lower wall of the bin is provided with discharge chutes 28 at each side and extending along the length of the 70 bin, and these chutes are controlled by valve or gate members 29 which may in turn be actuated to open or close the same by suitable operating members 30.

In the operation of the device, the lime 75 from the kilns is carried by the conveyor 26 to a point above the screening device and deposited into the latter through the chute 27. The lime falls upon the reticulated plate or screen 18 which is being continuously reciprocated by the rod 22 and the crank 23. The movement of the screen causes the finer particles to pass through the holes in the screen and fall upon the bottom plate 19 which is inclined towards 80 the chute 20. The reciprocations of the screening device cause the particles from the plate 19 to slide or roll down the same and fall through the chute 20 into the storage compartment A. The coarser particles 85 or lumps which cannot pass through the holes in the reticulated plate or screen 18 are caused by the shaking movement to roll or slide down the screen and fall upon the 90 platform 8.

The scrapers 15 of the endless carrier device in moving across the platform 8 carry the deposited particles along the platform and over and upon the inclined wall or partition 7 until an inclined layer of the particles is formed thereon and upon the surface of this layer progressively as the layer progresses across the bin. It will be noted 100 that during this handling, separation and storing, that the coarse particles or lumps are at no time given any considerable momentum or stopped abruptly, with the result that there will be little or no breakage 105 of the coarser particles. The lime is withdrawn from the bin as desired for packing or shipping by means of the discharge chutes 28 which are controlled by the suitable gates 29.

110 While I have explained the application 115 of the invention to the handling, sorting and storage of lime for the purpose of demonstrating the nature of the invention, it will be understood that the invention is applicable to the handling, sorting and storage 120 of other similar fragile lump material and such other materials are to be comprehended within the meaning of the terms used throughout the specification and claims. It will also be obvious that various changes 125 in the details and arrangement of parts herein described and illustrated for the purpose of explaining the nature of the invention may be made by those skilled in the art within the principle and scope of the invention.

I claim:

1. In a sorting and storage device, a bin with an inclined partition dividing it into two compartments, a substantially horizontal wall extending from the upper end of the inclined partition, a screening device arranged to separate the material into relatively coarse and fine particles and to discharge the finer particles of the material directly into the compartment extending beneath the inclined partition and the coarser particles upon the horizontal wall, and means for carrying the material from the horizontal wall over upon the upper end of the inclined partition and upon the upper end of the inclined layer of material formed upon the partition progressively across the compartment.
2. In a sorting and storage device, a bin with an inclined partition dividing it into two compartments and a wall extending from the upper end of the inclined partition at least partially over the compartment extending beneath the partition, an endless carrier extending over the wall, inclined partition and the compartment over the partition, and having means for scraping material deposited upon said wall over upon the upper end of the inclined partition and

then upon the upper end of the inclined layer of material formed upon the partition progressively across the compartment, a screening device arranged to separate the particles into fine and coarse particles, deposit the fine particles in the compartment extending beneath the partition and the coarse particles upon the wall to be carried over into the other compartment.

3. In a sorting and storage device, a screening device for separating the material into coarse and fine particles, a storage chamber into which the fine particles are deposited, a platform upon which the coarse particles are deposited, a second storage chamber having an inclined wall connecting at its upper end to the platform to form an inclined extension of the same, and mechanism for moving the coarse material along the platform over upon the upper end of the inclined wall to form an inclined layer thereon of the material and then upon the upper end of the inclined layer of the material which is formed progressively across the second storage chamber.

In witness whereof, I hereunto subscribe my signature.

WILLIAM D. MOUNT.
